HOE HOLDER

Thomas F. Sliger, Littleton, Colo.

Application February 8, 1954, Serial No. 28,914

Term of patent 14 years

(Cl. D35—2)

FIG. 1

To all whom it may concern:

Be it known that I, Thomas F. Sliger, a citizen of the United States, residing at the city of Littleton, county of Arapahoe and State of Colorado, have invented a new, original, and ornamental Design for a Hoe Holder, of which the following is a specification, reference being had to the accompanying drawing, forming a part hereof.

The broken lines in Fig. 2, showing a hoe, are for illustrative purposes only.

I claim:

The ornamental design for a hoe holder, as shown and described.
